INTERMITTENT SIPHON DOSING DEVICE

Philip Legarra, West Los Angeles, Calif.

Application January 19, 1946, Serial No. 642,198

9 Claims. (Cl. 222—416)

1

My invention relates to the art of dispensing beverages and more particularly to devices adapted for fitting into a bottle through which beverages may be poured.

It is my object to provide a dispenser for beverages which may be fitted to a bottle neck in substitution for the cork or stopper of the said bottle and through which beverages contained in said bottle may be poured in automatically measured quantities.

It is my further object to provide my dispenser adapted for continuous pouring of measured quantities while the bottle is held in pouring position. This feature enables the user to pour out one measured quantity after another while holding the bottle in pouring position and renders unnecessary the returning of the bottle to upright position in order to pour more than one measured quantity.

Another object of my invention is to provide a variable time limit between pouring cycles. By the addition in my dispenser of a tube during construction, I am able to materially decrease the time interval between the emptying of a measured quantity of a beverage from my dispenser and the refilling of the said dispenser to a point where emptying of the said dispenser again commences.

It is likewise my object to provide my dispenser of economical and rugged construction lacking in any moving parts and adapted for easy cleaning.

Other objects and advantages of this invention, it is believed, will be apparent from the following detailed description of a preferred embodiment thereof as illustrated in the accompanying drawings.

Fig. 1 is a perspective view of my invention.

Fig. 2 is a rear elevational view of my invention with casing partly cut away.

Fig. 3 shows a longitudinal section of my invention taken along the line 3—3 of Fig. 2.

Fig. 4 shows a part of my invention adapted with means for decreasing the time interval between pouring cycles.

Fig. 5 shows in perspective my dispenser filling tube.

Fig. 6 shows in perspective my dispenser siphon cup.

Referring to the drawings, the bottom casing 10 is orificed at 12. Extending through said orifice 12 in sealed relationship with the said bottom casing 10 is the filling tube 14 which has a cap 16 orificed at 18 and is opened at 20 and at the orifice 22. About the filling tube 14 is a cork 24 which may replace the ordinary cork of the bottle to be emptied.

2

A tube 26 having at its end the metering plug 28 extends through the filling tube 14 and through the orifice 18 of cap 16, being sealed with the said cap 16. A top casing 30 is press fitted in sealed relationship over the bottom casing 10 and is orificed at 32, carrying in sealed relationship through the said orifice the spout 34. The top casing 30 is also orificed at 36 and carries in sealed relationship therethrough the breather tube 38. The spout 34 extends into a siphon cup 40 which is orificed at 42 to receive the tube 26 and which has a baffle plate flange 44 adjacent the extremity 46 of the breather tube 38.

My dispenser may be constructed in any suitable common manner, but brass tubing and brass sheet stock are preferred with the exception of the cork 24 which may be of suitably resistant rubber. All metal parts may be soldered together for support, and thus the spout 34 and breather tube 38 are carried by the top casing 30 while the siphon cup 40 is carried by the tube 26 and the cap 16, the tube 26 receiving its support from the filling tube 14 and the cap 16.

In operation, my invention functions on an air belt and siphon principle. My dispenser is first placed in the bottle, replacing the bottle cork or stopper where it seats on the cork 24. For pouring, the bottle is tilted to a position whereby the spout 34 is down and approximately vertical. Air rises through the spout 34 into the cup 40, thence through the tube 26 and through the metering block 28 into the bottle. The air entering the bottle permits fluid therein to pass through the filling tube 14 and out the orifice 22 into the dispenser proper.

The filling of the dispenser proper continues until the fluid level reaches the inner edge 48 of the spout 34, when siphoning commences. At this point, air is cut off from the tube 26 and thence 40 to the bottle, and fluid no longer issues from the orifice 22. The breather tube 38 permits an atmospheric pressure to be maintained with the dispenser for siphoning purposes, and the flange plate 44 over the breather tube extremity 46 prevents any spilling of fluid through the said breather tube during the dispenser filling operation.

Siphoning of the fluid in the dispenser continues until the fluid level has reached the edge 50 of the cup 40. When the fluid level has reached the edge 50 of the said cup 40, fluid no longer passes through the spout 34 and air is free to rise again through the tube 26 into the bottle, commencing another cycle.

The time interval between pouring cycles consists of the time necessary for air to enter the

bottle through the tube 26 and permit fluid to fill the dispenser to a level with the inside edge 48 of the spout 34. Normally some fluid enters the tube 26 during the operating cycle by virtue of the inertia of the fluid entering the dispenser in the usual manner and as a result of reduction of pressure in the tube 26 during siphoning. This fluid does not immediately drain out, and when the siphon is broken and air again starts through the tube 26, the remaining fluid presents an obstacle through which the air must flow. The entering air also tends to hold the fluid in the tube 26 and in fact pushes some of it out of the tube 26 and back into the bottle. This fluid obstacle lengthens the time needed for enough air to pass into the bottle to fill the head.

For lessening the time interval between pouring cycles, I have provided, as shown in Fig. 4, an inner tube 52 within the tube 26. The inner tube 52 is so disposed and fixed within the tube 26 that during the pouring operation it is against the top of the inner periphery of the said tube 26 and its innermost end is spaced from the metering plug 28. The fluid that enters the tube 26, through the plug 28, enters the tube proper but does not enter the inner tube 52, it clings to the walls of the tube 26 and flows into the space between tubes 26 and 52; thus during the dispenser refilling operation, air passing into the bottle by-passes the fluid obstacle between the tubes 26 and 52 by flowing through the tube 52.

I have found that in one embodiment of my invention, wherein was used simply the tube 26, the interval between pouring cycles was three seconds, whereas, with the inner tube 52 placed within the tube 26 in the same structure, the time interval was but one second. Thus, my dispenser might be constructed without the inner tube 52 for home use, for instance, wherein a relatively substantial time interval is desired between pouring cycles; and it might be constructed with the said inner tube 52 for commercial use, as in public purveying places where it is desired that the pouring cycles occur more frequently.

Since siphoning in my dispenser takes place only while the fluid level is between the inner edge 48 of the spout 34 and the edge 50 of the cup 40, it is apparent that the capacity of my dispenser may be varied by varying the distance into the casing 39 which the spout 34 projects.

Having fully described my invention, it is to be understood that I do not wish to be limited to the details herein set forth, but my invention is of the full scope of the appended claims.

I claim:

1. A device of the class described comprising: a casing adapted to coact with a container; a spout venting said casing; a siphon cup within said casing and about said spout; a tube venting said siphon cup and extending into said container; a second tube within said first tube venting said siphon cup; a filling tube projecting from said casing and extending into said container; and means for venting said casing independent of said spout and said filling tube.

2. A device of the class described comprising: a casing adapted to coact with a container; a spout venting said casing; a siphon cup within said casing and about said spout; a tube venting said siphon cup and extending into said container; a second tube within said first tube venting said siphon cup; a filling tube projecting from said casing and extending into said container; means for venting said casing independent of said spout and said filling tube; and a baffle within

said casing interposed between said filling tube and said venting means.

3. A device of the class described comprising: a casing adapted to coact with a container; a spout venting said casing; a siphon cup within said casing and about said spout; a tube venting said siphon cup and extending into said container; a second tube within said first tube venting said siphon cup; a filling tube projecting from said casing and extending into said container; means for venting said casing independent of said spout and said filling tube; and a baffle within said casing extending from said siphon cup and interposed between said filling tube and said venting means.

4. A device of the class described comprising: a casing adapted to coact with a container; a spout venting said casing; a siphon cup within said casing and about said spout; a tube venting said siphon cup and extending into said container; a second tube within said first tube venting said siphon cup; a capped filling tube projecting from said casing and extending into said container; and means for venting said casing independent of said spout and said filling tube.

5. A device of the class described comprising: a casing; a filling tube extending from within said casing and supported by said casing; means about said filling tube for coacting said casing with a container with said filling tube disposed within said container; a tube smaller in diameter than said filling tube carried within said filling tube and extending into said container; an inner by-pass tube within said smaller tube; a siphon cup within said casing receiving said tube; a spout supported by said casing and extending from within said siphon cup out of said casing; and a second tube within said casing venting said casing to the atmosphere.

6. A device of the class described comprising: a casing; a capped liquid passing tube extending from said casing, said tube opening within said casing; means about said tube for inserting said tube within a container; an air passing tube extending through said liquid passing tube into said container; a by-pass tube within said air passing tube; a siphon cup within said casing receiving said air passing tube; a spout extending from within said siphon cup to without said casing; an orifice in said casing; and a breather tube leading from said orifice to within said casing.

7. A device of the class described comprising: a casing adapted to coact with a container; a spout venting said casing; a siphon cup within said casing and about said spout; a tube venting said siphon cup and extending into said container; a second tube within said first tube venting said siphon cup; a capped filling tube projecting from said casing and extending into said container; means for venting said casing independent of said spout and said capped filling tube; and a baffle within said casing interposed between said capped filling tube and said venting means.

8. In a device for measuring liquid from a container, the combination with a casing containing a siphon, of a tube venting said siphon and extending into said container, a second tube within said first tube venting said siphon, and a filling tube projecting from said casing and extending into said container.

9. In a device for measuring liquid from a container, the combination with a casing containing a siphon, of a tube venting said siphon and extending into said container, a second tube with-

in said first tube venting said siphon, a filling tube projecting from said casing and extending into said container, and means for venting said casing independent of said siphon and said filling tube.
